UNITED STATES PATENT OFFICE

2,451,521

MAGAZINE LOADER

Alfred H. Uglum, Waterville, Iowa

Application January 9, 1945, Serial No. 572,044

1 Claim. (Cl. 86—47)

(Granted under the act of March 3, 1883, as
amended April 30, 1928; 370 O. G. 757)

1

The invention described herein may be manufactured and used by or for the Government for governmental purposes without the payment to me of any royalty thereon.

This invention relates to machines for loading cartridges into magazines.

A purpose of the invention is to provide a machine by means of which magazines for sub-machine guns and the like may be quickly, easily and automatically loaded with ammunition.

Other purposes of the invention will become apparent from the following description and drawings.

Reference is now had to the drawings in which:

Figure 1 is a front elevational view of a machine embodying the invention;

Figure 2 is a cross sectional view taken along the line 2—2 of Figure 1;

Figure 3 is a sectional view taken along the line 3—3 of Figure 1;

Figure 4 is a sectional view taken along the line 4—4 of Figure 1, and

Figure 5 is an enlarged cut-away detail view of the mechanism and cartridges as they enter the magazine.

In the use of sub-machine guns like the Thompson cal. .45 sub-machine gun, it is necessary to load the magazine or clip with the cartridges. While this may be done by hand for loading one clip, it becomes a tedious and somewhat tiresome task when a great many clips are to be loaded. One reason is the fact that the cartridges have to be forced into the clip against the resistance of an internal spring, and the resistance of the spring increases as more and more cartridges enter the clip. The present invention shows a mechanism by which the process of clip loading is greatly facilitated and improved.

In Figure 1, a vertically arranged raceway 10 is adapted to hold a number of cartridges 12 in a vertical column as shown. A back plate 14 is formed into a U-shaped channel 15 as also shown in Figure 3, just deep enough and wide enough to receive the rims 16 of the cartridges 12. Face plates 18 and 20 fastened against back plate 14 have extensions 22 and 24 projecting inwardly over the front of the channel 15, the extensions having their projecting edges beveled as shown in Figure 3 to fit loosely in the rim groove of the cartridges 12, thereby holding the cartridge rims in the channel 15 as shown. Faceplate 20 has a lower extension 21 rounded as shown, to guide the cartridges as they fall onto the ramp 25 and keep them in line.

Thus the column of cartridges 12 as seen in

2

Figure 1, is constrained into movement downward by means of gravity and securely though loosely held in the channel 15. The raceway 10 is made any convenient length to accommodate the desired number of cartridges 12 as shown. The raceway 10 is open at the bottom, permitting the cartridges to drop by gravity onto a guiding ramp 25 formed by plates 26 and 28 as shown in Figures 1 and 5.

10 A vertically reciprocating plunger 30, of rectangular cross section, is arranged to slide in a chamber 32 open at the top and bottom and formed between the sides 34, 36, 38 and 40. The top 42 of the plunger 30 is arranged to reciprocate to a low position at the base of the inclined ramp portion 28 as shown in Figure 1 and Figure 2, with all its travel above this point.

A shaft 44 having an external turning crank 46 and handle 48 is rotatably arranged in two horizontal bearings 50 and 52 formed in the vertical members 54 and 40, bearing 52 being made removable as shown for easy insertion of shaft 44 therethrough. An internal crank 56 is formed by bending shaft 44 as shown in Figure 2. A connecting rod 58 has its upper end pivotally connected to the lower end of the plunger 30 by means of a pivot pin 60 inserted through a horizontal bore passing through both the connecting rod 58 and the plunger 30 as shown in Figures 1 and 2. The lower end of the connecting rod 58 has a U-shaped transverse groove 62 to accommodate the crank 56, and a pin 64 through its projecting ends to retain the crank in the groove 62.

35 It is thus apparent that turning the handle 48 in a clockwise direction as indicated by the arrow 66 will cause the plunger 30 to reciprocate vertically.

The column of cartridges 12 in the raceway 10 forces the lowest cartridge into the position 68 where it rests directly on the top 42 of the plunger 30.

40 A magazine or clip 70 of the usual type employed in the Thompson sub-machine gun is inserted, open end downward, into the machine as shown. The frame of the machine is formed as shown, with a side wall 72 and a back wall 74 which is formed with a channel as shown in Figure 3 extending upwards from the line 76 of Figures 1 and 2, to accommodate the rear longitudinal projection 78 of the clip 70. A stud 80 formed in the wall 72 serves to hold the top of the clip 70 in the machine as shown, and to prevent vertical movement thereof. A curved depression 82 is formed in wall 72 to permit the

upper rim 84 of the clip 70 to enter without interference. The wall 72 is also cut away as shown at 86 so the clip may be held with the fingers as it is inserted and withdrawn from the machine. The right hand lower lip 88 of the clip is supported as shown in Figure 5 by the curved portion of the wall 72.

With the clip 70 in place and the raceway 10 full of cartridges as shown in Figure 1, the handle 48 is turned continuously in a clockwise direction. The plunger 30 forces cartridge 68 upwards into the lower opening of the clip 70, forcing it in against the resistance of the projection 90 of the spring follower inside the clip. As the handle 48 is turned again, the next cartridge, having rolled onto the top of plunger 30, is also forced upwards into the clip, and so on as seen in Figure 5, until the clip is full, when it is removed from the machine by gripping at the position of the cutout 86 and pulling sidewise.

The top 42 of the plunger 30 may be flat as shown, or may have a shallow transverse groove 92 as shown in Figure 5 to partly receive the rounded side of the cartridge. The upper portion 94 of the wall 40 is slanted as shown in Figure 2 to permit tilting the clip during insertion and extraction.

While metal is preferred, the machine may be made of any other suitable material if desired.

While the specification sets forth a description of the invention in specific terms, it is to be understood that variations may be made in the size, shape, materials and arrangement without departing from the scope of the invention as claimed herein.

I claim:

A filler for sub-machine gun magazines having

an open end, including a support for holding a magazine with open end downward, means arranged on said support beneath the open end of said magazine for pressing a cartridge upwardly into the magazine comprising a plunger mounted for vertical reciprocating movement, a rotatable shaft disposed beneath the plunger, a crank on said shaft, a connecting rod rotatably connected at its lower end to said crank and pivotally connected at its upper end to said plunger, and means for rotating said shaft, and gravity actuated means carried by said support for delivering cartridges one by one onto said plunger comprising a hopper elevated relative to the said plunger provided with vertical guide grooves for slidably engaging the rims of cartridge cases to maintain the cartridges in alignment one above the other and a passageway communicating at an angle with said hopper adjacent the bottom of the vertical guide grooves for delivering cartridges one by one from the guide grooves to the top of said plunger.

ALFRED H. UGLUM.
